UNITED STATES PATENT OFFICE.

FREDERICK C. KESSLER AND ERNEST L. KESSLER, OF ST. LOUIS, MISSOURI.

ATTACHMENT FOR STOVES AND RANGES.

No. 844,142.

Specification of Letters Patent.

Patented Feb. 12, 1907.

Application filed April 27, 1906. Serial No. 313,978.

To all whom it may concern:

Be it known that we, FREDERICK C. KESSLER and ERNEST L. KESSLER, citizens of the United States, residing in the city of St. Louis, in the State of Missouri, have invented 5 certain new and useful Improvements in Attachments for Stoves and Ranges, of which the following is a full, clear, and exact description, reference being had to the accompanying drawings, forming part of this specification.

Our invention relates to an attachment for stoves and ranges designed for service as a support for the various implements used in 15 connection with stoves and ranges—such, for instance, as stove-lid lifters, pokers, shovels, and grate-shakers.

The object of the invention is to provide a support of the character named whereby the 20 stove implements may be disposed in congregated positions when not in use and so held that they may be readily grasped and removed from the support when either implement is to be used.

25 Figure I is a perspective view of our attachment shown applied to a fragment of a stove or range. Fig. II is a vertical transverse section taken on line II II, Fig. I. Fig. III is a vertical longitudinal section taken on 30 line III III, Fig. II, through the portion of the stove or range illustrated and showing the attachment in rear elevation. Fig. IV is an inverted view of the attachment. Fig. V is a front elevation illustrating a modification.

35 A designates a fragment of the rim of a stove or range to which our attachment may be applied.

1 designates a plate that forms the main 40 body of our attachment and which is adapted to be secured to the rim of the stove or range at any convenient point. The body-plate 1 is provided with one or more pockets 2, that are adapted to receive the point of a stove-lid lifter, as shown by dotted lines, Fig. I, two of said pockets being preferably provided. Extending inwardly from one side of the body-plate is a notch 3, which is adapted to receive a poker, as shown in dotted lines, Fig. I. Extending outwardly from the outer edge of the 45 body-plate is a hook 4, that is adapted to receive the handle of a fire-shovel, as shown in dotted lines, Fig. I, and extending upwardly from the top of the body-plate are pairs of fingers 5, arranged parallel with each other

and adapted to receive a grate-shaker. (Not shown in the drawing.)

The rear edge of the body-plate 1 is adapted to be placed against the rim of a stove or range top, and extending upwardly from the 60 inner edge of the plate is a tongue 6, that is adapted to rest against the outer face of said stove or range top rim. At the lower side of the body-plate, and preferably integral therewith, is a bifurcated lug 7, the arms of which 65 are sufficiently separated from each other to provide for the reception of a bolt that may be introduced between the arms and extend rearwardly for the purpose of securing a clamping member to be presently described. 70

8 are arms formed integral with the body-plate of the attachment and extending rearwardly therefrom, as seen in Figs. III and IV, these arms being so disposed relative to the tongue 6 at the top of the body-plate that 75 they will protrude beneath the edge of the stove or range top rim, while said tongue fits against the outer face of said rim.

9 is a clamp-plate that is adapted to be placed against the inner side of the stove or 80 range top rim. This clamp-plate is apertured to receive the arms 8, which are passed therethrough near the ends of the clamp-plate, and it is also centrally apertured to receive the binding-bolt 10, which is seated between the lugs 7 of the body-plate. 85

It will be seen that when the parts are applied in the positions shown and described and the nut on the binding-bolt is tightened the body-plate and clamp-plate are drawn 90 tightly to the stove or range top rim, and as a result the attachment is securely held to said rim and the clamp-plate is held in alinement with the body-plate, due to the seating of the arms 8, which are carried by the body-plate, 95 in the apertures in the clamp-plate.

It is obvious that other means for attaching our attachment to a stove or range might be utilized and the clamping device described be dispensed with. For instance, apertures, 100 as shown at *a* and *b*', might be formed, respectively, in the stove or range top rim and the tongue of the body-plate of the attachment and a bolt passed through these members to connect them. 105

In Fig. V we have shown a modification in which the bifurcated lug 7' is detachable from the body-plate of the attachment and is preferably held to said body-plate when in use by forming a dovetail joint between it 110

and the plate. In other respects the attachment is the same as that previously described.

We claim—

1. An attachment for stoves or ranges comprising a plate adapted to receive implements appertaining to said stove or range and having a tongue slanting upwardly from the plate and adapted to rest against the outer face of the top rim of the stove or range to hold the plate against downward movement when clamped, and means for clamping said plate to the top rim of the stove or range, said clamping means comprising a downwardly-extending lug and rearwardly-extending arms carried by said plate and forming parts thereof, a clamp-plate adapted to receive said arms, and a binding-bolt for connecting said lug and clamp-plate, substantially as set forth.
2. An attachment for stoves and ranges, comprising a plate adapted to receive implements appertaining to said stove or range

and having a tongue slanting upwardly from the plate and adapted to rest against the outer face of the top rim of the stove or range to hold the plate against downward movement when clamped, and means for clamping said plate to the top rim of the range or stove; said clamping means comprising a central bifurcated lug extending downwardly from the plate, arms extending rearwardly from the plate, a clamp-plate having perforations through which said arms are adapted to pass and having a central aperture, and a binding-bolt adapted to pass through said central aperture to connect the clamp-plate to the lug, substantially as set forth.

FREDERICK C. KESSLER.
ERNEST L. KESSLER.
